BLIND STITCH SEWING MACHINE

Franz Mikolas, Vienna, Austria

Application February 28, 1948, Serial No. 12,076
In Austria March 12, 1946

10 Claims. (Cl. 112—176)

1

The invention relates to machines or accessory appliances for sewing machines for producing blind stitch or piqué seams in which a blind stitch needle passes—at every working stroke—through a thread loop formed by a looper as well as through the work temporarily lifted by means of a fabric bender whereupon i. e. after the return stroke of the needle, the feeding motion of the work is carried out.

The machines and devices hitherto disclosed for this purpose—irrespective of whether the looper travels along a path composed of rotary and longitudinal motions, or whether it executes a simple oscillating movement along a circular arc—are all characterized by the looper itself conveying the thread picked up from the needle in the shape of a loop to the needle entering point and holds it there until the stitch is made. For this purpose the looper must be provided with two nose-shaped catchers or pointed grippers for holding the loop, and should additionally execute a motion enabling it to pass from the needle exit point directly over the fabric roll produced by the fabric bender, and then again to descend to the needle entering point. As, however, in this case the looper is open towards the fabric to be sewn, there is the danger that the thread loop may be stripped off from the looper, and that the latter may get stuck by clamping, particularly when working fabrics of varying thickness e. g. padded ones. The passing of the looper over the fabric roll is realized in piqué devices, having a looper oscillating along a circular arc, in such a manner that the latter executes its oscillating motion in a plane chiefly located behind the needle plane and slanting upwards in the fabric feeding direction so as to compel the looper first to mount and then to descend. With an arrangement of this kind, however, the conveyor cannot be sufficiently approached to the needle, and for this reason the stitching of the work can only be started at a certain distance from the fabric margin.

The object of the invention is a blind stitch and piqué device which may be used as a self-contained machine, or as an accessory appliance for sewing machines, said device eliminating the above mentioned drawbacks by fixing in the range of the needle path a loop catching nib (loop catcher) by means of which the thread loop supplied to it by the looper is located above and below the needle guide for the subsequent throughstitch of the blind stitching needle. As not only the loop catcher but also the looper, preferably oscillating in a manner known along

5 a circular arc, are separated from the work by a cover plate over the whole length of the moving range, the formation of the loop and the stitch are perfectly independent of the nature and the thickness of the work. Besides, the looper path, ending with the thread loop being picked up by the catcher, is located in front of the needle plane, except the portion of the path necessary for picking up the thread from the blind stitching needle, which renders possible a conveying arrangement permitting of seaming the workpiece from its very margin.

10 The drawing represents, by way of example, two embodiments of the subject matter of the invention, Fig. 1 being a lateral elevation, partly in section, of a piqué device employed as an accessory to a sewing machine, immediately after the beginning of the return motion of the needle, whereas Fig. 2 shows the same device at the 15 moment at which the needle begins its subsequent forward stroke. Fig. 3 is a longitudinal section through the piqué device, seen from the right-hand side of Fig. 1, whereas Fig. 4 is a section taken along the line IV—IV of Fig. 3. 20 Fig. 5 is a lateral elevation, and Fig. 6 a front elevation of the looper. The Figs. 7 and 8 are a lateral elevation, partly in section, and a plan, 25 diagrammatically showing the stitching plate together with the fabric bender, and its drive. Fig. 9 represents a blind stitching and piqué machine according to the invention in front elevation seen from the operator's side with a partial section through the fabric guiding foot, whilst Fig. 10 is a lateral elevation of the same embodiment. The Figs. 11 and 12 are views in full size 30 of the stationary fabric guiding foot (cover plate), Fig. 11 being a plan showing the manner in which the stitches are made, whereas Fig. 12 is a section taken on the line XII—XII of Fig. 11.

35 The piqué device represented in the Figs. 1—8, suitable for stitching through and, in particular, for blind stitching, is provided with a presser foot 4 (Figs. 3, 4), fastened by means of a screw 2 to a presser-bar 3. The foot part of the presser foot, preferably fitted with a level bottom, is opposed to the fabric feeding direction x, its upper side 4a, 4b obliquely sloping towards its bent-up free end, so as to form a step 1. In the presser foot 4 a needle groove 6, curved in its longitudinal direction, is provided below the step 1 transversally to the feeding direction x of the workpieces 5 to be seamed (Figs. 1, 2), said channel serving as a guide for the blind stitching needle 7, and being interrupted on a part of its length 50 by a central recess 8 (Fig. 4) passing through

the presser foot 4. To the end of the needle groove 6 a channel 9 (Figs. 3 and 4) is directly joined, obliquely opening into the presser foot bottom, so as to create the necessary space for the root of the thread loop 10 forming. The margin of the foot recess 8, facing the user of the sewing machine, is cambered and passes, towards the entrance point of the needle 7, into a surface depression 11 bordered by an arc, so that between the latter and the front part of the needle groove 6 a loop catching nose 12 is formed at the border of the foot recess 8. In order to enable this loop catching nose 12 (Figs. 1-4) to accomplish its task it is undercut to form a rest 13 for the lower thread part of the loop 10, said rest beginning at the surface depression 11, and the recess 8, and reaching below the needle groove 6. Besides, said nose is made to protrude in the upward direction somewhat beyond the edge of the needle groove 6, so that the upper thread part is freely laid above the needle groove 6, in consequence whereof the blind stitching needle 7 may freely enter into the thread loop 10.

The blind stitching needle 7 is arranged on an oscillating arm 16 formed as a part of a circular arc by means of a needle clamp 15 provided with the thread guides 14 (Figs. 1 and 2), said arm executing oscillating movements about a journal bisecting the axis of the presser-bar 3, and being located in parallel to the fabric conveying direction X (Figs. 3 and 4). In order to attain this object a clamping (gripping) piece 17, slid on the presser-bar 3 just above the presser foot 4, is fastened in such a manner that its medium part is divided into two lateral cheeks 17a by means of a slot arranged in parallel to the axis of rotation of the oscillating arm 16, one of said cheeks being split by a transverse slot 18 into an elastic lug, and fixing the clamping piece 17 on the presser-bar 3 when tightening a tension screw 19 passing through the cheek 17a. This clamping piece 17 serves as support for the oscillating arm 16 by passing into a stirrup 20 (Figs. 1, 3) which laterally embraces the clamping piece 17, said stirrup engaging on both sides a center-mark like depression of the clamping piece 17 by means of a pointed and threaded pin 22, secured in its position by a nut 21. In this manner the tilting motion of the oscillating arm 16 is made possible. The drive of the oscillating arm 16 can be realized in different manners. With the piqué device, designed as accessory for the usual sewing machine according to the embodiment illustrated, said drive is derived from the needle bar 23 of the sewing machine for which purpose an arm 24, clamped to the needle bar 23, is connected to the oscillating arm 16 by way of a link 25.

A rotary bolt 28, provided at its upper part with a bevel gear wheel 27, is journalled at its one end in an arm 26 obliquely sloping at the upper end of the presser foot 4, and at its other end in the correspondingly inclined upper side 4a, 4b of the presser foot 4, for which purpose the lower pointed bolt end engages a center-mark like depression of the presser foot 4, whilst a threaded pin 30 passing through the arm 26 and securely fixed by the nut 29 rests with its point in a center-mark like depression of the rotary bolt 28, thus keeping it freely pivotable. It has been found useful to fix the bearings of the rotary bolt 28 in such a manner that the vertical plane, located through the blind stitching needle 7, intersects the central bolt axis in the middle of the length of said bolt, but in any case above the needle groove 6. Consequently, the upper bearing of the rotary bolt 28 is located in front of the

plane of the needle groove 6, whilst its lower bearing is placed behind said plane. Moreover, the rotary bolt 28 carries a clamping (gripping) body 31 similarly shaped as the clamping body 17 which takes up in a bore the shaft 32 of the looper 33, designed at the same time as thread spreader. The fixation of the clamping body 31 to the rotary bolt 28 and to the looper shaft 32 in the clamping body 31 is effected by the clamping screw 34 (Figs. 2, 3).

With the bevel gear wheel 27 a toothed arc 35, fixed to the oscillating arm 16, is made to register, whereby a movement of oscillation reaching to about 135°, is imparted to the rotary bolt 28 and consequently to the looper 33 by the motion of the needle bar 23, said motion taking place counterclockwise during the forward stroke of the blind stitching needle 7, and clockwise during the return stroke for the machine being contemplated from above (arrow y, Fig. 4). The oscillation range and the oscillation position of the looper 33 are determined in such a manner that at the end of its return stroke (position Fig. 1) it recedes completely behind the needle groove 6, whereas during the forward stroke it lays over the nose-shaped catcher 12 the thread loop 10 picked up by it (position Fig. 3).

The looper 33 projecting as small foot from an oblique undercutting 36 (Figs. 5, 6) of the shaft 32, and terminating in a point 37 has, seen in plan, approximately the shape of a scalene triangle, whose smallest angle determines the point 37 of the looper. Together with the adjoining side of the triangle adjacent to the right angle, this point 37 is unilaterally inserted in an even-faced upright lateral wall 38 of the looper 33, whereas the hypotenuse, somewhat curved outwardly in an arc-shaped manner, forms the other lateral border edge 39 of the bottom 40 to which a slight convexity is imparted, and which preferably slopes somewhat towards the point 37, but is more inclined towards the lateral wall 38. Beginning from the border edge 39 the said bottom passes into the upper side of the looper by convexly cambering up to the lateral wall 38 e. g. along a part of the surface of a cone, so that also the upper part beginning from the point 37 slantly ascends towards the shaft 32, and is made to enlarge laterally. The looper 33 is fastened in such a manner in the clamping body 31 that its even lateral wall 38 is directed inwardly i. e. towards the rotary bolt 28, whereas its bottom 40 leaves open a slot between the looper 33 and the presser foot 4, sufficient for the unhampered passing of a thread even in the inclined position of the looper caused by the oblique position of the rotary bolt 28. The extreme slanting position is obtained, when the looper 33 together with the shaft 32 attains its foremost position in respect to the user of the machine.

The piqué device comprises further a fabric bender 42 (Figs. 1, 7 and 8) which executes a reciprocating motion through an aperture of the stitching (needle) plate 41 (Figs. 7, 8) lifting the fabric and the inset parts 5 to be "piqué" within the recess 8 of the presser foot, conveying same during the seaming action into the range of the blind stitch needle 7. The drive of the fabric bender 42 is e. g. derived by way of a double-armed lever 43 from a cam 44 (Figs. 7, 8), the latter being fastened on the conveyor shaft 45, generally used in sewing machines and showing a level-faced section 46 recessed in respect to the remaining circumference which has the shape of a circular cylinder. An adjusting device, not shown in the drawing but of known

design permits of an optional vertical displacement of the fabric bender 42 for the purpose of adapting it to the thickness of the workpieces to be dealt with.

The mode of operation is the following:

First the position illustrated in Fig. 1 will be considered in which the blind stitching needle 7 has just passed through the fabrics 5, to be "piqued," presented to said needle by the fabric bender 42. At this moment the looper 33 has reached the end of its return stroke, and has thus retreated behind the needle groove 6. As soon as the needle 7 begins to retreat in the direction of the arrow *z* (Fig. 1), the forward stroke or advance of the looper 33 is synchronously started, said stroke being carried out in the clockwise direction (arrow *y*, Fig. 4), the looper gripping from below the portion of the thread 10 between the fabric 5 and the needle eye slightly above the blind stitching needle 7, said thread portion losing its tension and standing up a little with the blind stitching needle 7 receding. This portion of the thread 10 is completely shifted on the looper 33 up to its undercutting 36, and is enlarged and spread out by 25 same to a wide loop 10. After the needle 7 has released the fabrics 5 the fabric bender 42 together with the fabrics 5 descends, under the action of the double-armed lever 43, reaching the range of the cam section 46, for the duration of the fabric conveyance by means of the usual transporting devices. In consequence of the forward slanting position of the rotary bolt 28 the looper 33 will, in the course of its forward stroke, finally reach a position so low that the lower part of the thread loop 10 is caught by the rest 13 of the nose 12, said rest being located below the needle groove 6 (Fig. 2), whereas the upper thread portion is laid above the needle groove 6. At the subsequent operation (opposite to the arrow *z*, Fig. 1) of the needle 7 some passes through the thread loop 10 and shortly afterwards again through the fabrics 5, lifted by the fabric bender 42, whereas the looper 33 (in the opposite direction to the arrow *y*, Fig. 4) returns into its initial position. For blind stitching operations the fabric bender 42 is to be adjusted in such a manner that the lower fabric is not entirely stitched-through. If, however, the fabric bender 42 is also provided with a groove within the range of the needle groove 6, and if the stroke of the fabric bender 42 is adjusted to a sufficient length, throughstitching work can also be carried out on this device.

The machine according to the Figs. 9-12 may be of any type known in which the conveyor and the fixed part of the fabric bending device are fastened to the machine head 51, whereas the movable part of the fabric bender, acting on the work from below, is arranged on the bottom part 52 of the machine.

In the manner known the machine head 51 is provided with the thread tension regulator 53, the thread guide 54, and the stitch length adjuster 55. On a transversal shaft 56 journalled in the machine head 51, whose oscillating motion is derived from the main shaft in a manner known, a two-armed oscillating lever 58 is fixed to an arm 57 of the machine head 51 extending towards the operating side, whereby the one lever arm carries the needle clamp 59 with the curved blind stitching needle 60 and the thread feeding device 61, whereas the other is provided with the bevel gear segment 62 for driving the looper 63. Same is adjustable in the vertical direction and held by the clamp 64, fitted to the

free end of a rotary bolt 65, whose other end carries a pinion registering with the segment 62. The axis of rotation of the rotary bolt 65 journalled within the machine-head arm 57 is located before the vertical plane of the needle path, and is inclined towards the latter as well as towards the vertical plane passing through the lowest point of the needle path in the direction of the fabric feed *x* as to intersect the needle path on its stitching-in side.

The fabric guiding foot 67, forming the stationary part of the fabric bender and carrying at its surface the loop catcher 68, is rigidly fastened to the arm 52 of the machine-head 51, extending towards the operating side, below the movable parts of the piqué device described, arranged on the machine-head 51, said foot serving at the same time as cover-plate separating these parts of the piqué device from the fabrics to be "piqued."

The fabric guiding foot 67 (see in particular the Figs. 11 and 12) passes from the fastening part 67a, provided on top with fitting faces and a longitudinal groove, by way of recesses in the direction of the width and of the thickness, into the foot part 67b bent up against the fabric feeding direction *x*. Besides, its otherwise even-faced bottom shows a continuous circular groove 67c, shaped according to the surface of a circular cylinder, said groove corresponding to the cross-section of the fabric bender 15, movably supported on the machine base 52. A closed slot 67d of the fabric bender foot beginning at the fastening end 67a, extending up, to beyond the needle path, and narrowing in the direct range of the latter, offers, in its wider part, sufficient space for the fabric conveyor, not shown, whilst permitting of the passage of the fabric bender in its narrow fore-part. Contiguous to the fastening part 67a a milled recess, according to a circular cylinder, is provided to correspond to the radius of the needle path, the right-hand side border wall 67e facing the bent-up foot part 67b of said recess and serving as guiding ledge for the blind stitching needle 60, whereas—on the left-hand side—same is limited by a needle groove 67f, facilitating the threading of the needle. In this milled recess, adapted to its curvature, small guiding plates 69, 70, 71 are fastened by screwing to both sides of the slot 67d, of which the plate 70 is provided with a projection slightly protruding beyond the edge of the narrowed slot part 67d, said projection being chamfered below, and acting as guide for the lower part of the thread loop. The small plates 70 and 71 of which the latter is obliquely cut on the slot side, are shortened in the range of the needle groove 67a by the width of the latter, and are used as additional abutments against a flexure of the blind stitching needle 60 in the fabric feeding direction. On top, the small plate 69 is chamfered in order to prevent the blind stitching needle 60 from impinging, even in case of a displacement of the fabrics, so that it may glide off unimpaired. On the left edge part of the fabric guiding foot 67 the stationary loop catcher 68 is fastened between the up-turned fore-part 67b of said edge, and the needle groove 67f, whereby a spacing sheet (distance sheet) 72, accounting for the thickness of the thread, is inserted in-between. The nose-shaped catcher 73 protruding near to the needle path in the narrow slot part 67d is rounded off downwards and in front, and carries at the apex of the circular fore-edge a

pin 74 bent—in its lower part—backwards to the needle path and acting as a loop holder.

The movable fabric bender horn 75, cooperating with the fixed fabric bender foot 67 is elastically journaled in respect to the latter in a fabric bender casing 77, pivotal about an axle 76 of the machine base 52, said horn being provided—in the range of the needle path—with an aperture for the fabric bender not shown. The tilttable fabric bender holder and its driving parts are likewise lodged in the fabric bender casing 77. A strongplate spring 79 acting on the carrier 78 of the fabric bender casing 77 keeps it permanently in the position of use, determined by a stop 80 on the carrier 78, out of which the casing can only be lowered against the action of the spring 79 by knee drive (indicated by an operating member 81 acting on the carrier 78) for the purpose of introducing or withdrawing the fabrics to be seamed.

The vertical adjustment of the fabric bender casing 77, and consequently of the horn 75 and the fabric bender, according to the thickness of the workpieces to be dealt with, is effected by means of a set screw 82, provided with a scale which is attached to the casing base 52. Under the action of the plate spring 79 the stop 80 of the carrier 78 is permanently made to rest against the conical end 83 of said screw. By turning the screw 82, which provokes an axial displacement of the cone 83 in one or the other direction, a slight tilting motion is imparted to the carrier 78 by or against the action of the spring 79.

In order to pass readily from blind stitch to through-stitch e. g. in case of padding work the fabric bender, having an upper edge, stepped according to the needle thickness, is displaceable in its holder by a needle thickness upwards and by the said step sideways e. g. by means of a rotary eccentric bolt, provided with a handle accessible from outside through an aperture of the fabric bender casing 77.

When the through-stitch of the blind stitching needle 60 is completed the looper 63, located at that moment behind the needle plane, starts on its active motion during which it picks up the thread loop left behind during the return stroke of the blind stitch needle 60, conveying it to the stationary loop catcher 68 along a curve initially ascending. The chamfer on the projection protruding over the slot 67d of the small guide plate 70 then takes charge of the secure guidance of the lower thread loop portion below the nose-shaped catcher 73 of the loop catcher 68. The upper portion of the thread loop is laid around the loop holder pin 74, provided on the nose-shaped loop catcher 73, by means of the small foot 63a of the looper 63 which—owing to the support of the rotary bolt 65 described—reaches its terminal position by way of a somewhat steep ascending curve. This phase of operation is shown in Fig. 11. At the subsequent active operation of the blind stitching needle 60 the small foot 63a of the receding looper 63 releases the loop, which narrowed by the tension of the thread, glides off from the nose-shaped catcher 73 of the loop catcher 68, rounded off in front and below, and is fixed and tightened by the connecting stitch being the result of the subsequent through-stitch. If after the completion of the operating phase, visible in Fig. 11, the work is to be interrupted and the "piqué" fabrics are to be removed, same need but be drawn out in the fabric feeding direction x after the fabric bender casing 77 will have been lowered by the pull mem-

ber 81 operated by means of the knees. Then the thread loop, prevented by the holding pin 74 of the nose-shaped catcher 73 from gliding from the small looper foot 63a is automatically ruptured at its front edge so that an undoing of the piqué seam is avoided. In this connection the blind stitching needle 60 is saved from bending in the fabric feeding direction by the additional abutment on the small guide plates 70, 71.

Having now particularly described, and ascertained the nature of my said invention, and in what manner the same is to be performed, I declare that what I claim is:

1. A blind stitch and piqué device, whether adapted for use as a self-contained machine or as a sewing machine attachment, which comprises, in combination with work feeding and bending means, a looper for forming a thread loop, a blind stitch needle, a presser part adapted to clamp the work and separating the work from the looper, said presser part having an opening for the work to be sewn and a groove for guiding the needle, a loop catching nose being provided in the edge of said opening for stripping the thread loop from the looper and laying it above and below the needle guiding groove.

2. A device as set forth in claim 1, in which the loop catching nose has a recess extending below the needle guiding groove.

3. A device as set forth in claim 2, in which the loop catching nose has a boss extending above the needle guiding groove.

4. A device as set forth in claim 1, in which said presser part has a depression for the thread in front of the loop catching nose.

5. In combination with a machine head, a blind stitch and piqué device, comprising a looper for forming a thread loop, a blind stitch needle, a presser part rigidly connected to the machine head and separating the work from the looper, said presser foot having an opening for the work to be sewn and a groove for guiding the needle and a loop catching nose provided at the edge of said opening for stripping the thread loop from the looper and laying it above and below the needle guiding groove, said loop catching nose having a thread holding pin which protrudes beyond the upper edge of said nose.

6. A device as set forth in claim 5, in which the loop catching nose is rounded on its front edge and bottom.

7. A device as set forth in claim 6, comprising additional guiding means which are provided on the stitching-in side of the needle path, and are adapted to prevent the lateral deviation of the blind stitch needle in the work feeding direction.

8. A device as set forth in claim 5, in which one of the edges of the loop catching nose forms the front limit of the needle guiding groove, and in which the bottom part of the thread holding pin is bevelled off in the work feeding direction, a guiding surface for the lower leg of the loop being provided behind said edge of the loop catching nose.

9. A device as set forth in claim 8, in which the presser foot has a longitudinal opening for the work feeding and bending means and in which the guiding surface for the lower part of the loop extends laterally beyond said opening.

10. In combination with a machine head, a blind stitch and piqué device, comprising a looper for forming a thread loop, a blind stitch needle, a presser part rigidly connected to the machine head and separating the work from the looper,

said presser foot having an opening for the work to be sewn and a groove for guiding the needle and a loop catching nose provided at the edge of said opening for stripping the thread loop from the looper and laying it above and below the needle guiding groove, said loop catching nose having a thread holding pin which protrudes beyond the upper edge of said nose, the looper being pivotally movable about an axis which is inclined both against the vertical plane of the needle path and against a vertical plane laid through the nadir point of the needle path in the work feeding direction, the pivotal axis of the looper intersecting with the needle path on

the stitching-in side of the work, the looper thus being adapted to lay the upper leg of the loop around the thread holding pin.
